UNITED STATES PATENT OFFICE.

EDWARD J. KINGSBURY AND HARRY T. KINGSBURY, OF KEENE, NEW HAMPSHIRE.

TOY AEROPLANE.

1,347,814.

Specification of Letters Patent.

Patented July 27, 1920.

Application filed July 17, 1919. Serial No. 311,671.

To all whom it may concern:

Be it known, that we, EDWARD J. KINGSBURY and HARRY T. KINGSBURY, citizens of the United States, residing, respectively, at Keene, in the county of Cheshire, State of New Hampshire, have invented certain new and useful Improvements in Toy Aeroplanes, of which the following is a description, reference being had to the accompanying drawing and to the figures of reference marked thereon.

This invention relates to improvements in toy aeroplanes.

The object of the invention is to provide an aeroplane of this character in which the fuselage, the two planes and running gear carrying the spring propelling means are made separate and independent of each other and locked together by interlocking ears carried by the running gear and a single removable bolt.

Another object of the invention is to mount the running gear on the plane so that it can be turned to cause the aeroplane to travel in a circle, and the turning of the running gear causes the planes to tilt or bank so that the plane will more readily follow the course set by the wheels of the running gear.

A still further object of the invention is to provide an aeroplane in which the propeller takes its power from a frictionally driven wheel near the tail of the fuselage and at the same time providing a simple, cheap and effective aeroplane having certain details of structure and combination of parts hereinafter more fully set forth.

In the accompanying drawings:

Figure 1 is a side elevation of our improved toy aeroplane;

Fig. 2 is a vertical longitudinal sectional view showing the means by which the wheels may be turned and the driving means for the propeller;

Fig. 3 is a front elevation;

Fig. 4 is a front view of the device, partly in section, showing the running gear turned to cause the aeroplane to travel in a circle and showing the planes slightly banked; and

Fig. 5 shows an enlarged longitudinal sectional view.

Referring more in detail to the drawings,

1 represents the fuselage which is preferably made of an elongated narrow form similar to the ordinary flying plane and is made of sheet metal or the like. The fuselage tapers both forwardly and rearwardly from the point 2, as indicated at 3 and 4, and is provided with an opening 5 in its upper face in rear of the point 2, as clearly shown in Fig. 2 of the drawings. This opening forms the car for the passengers and below the opening is a seat 6 upon which a toy figure may be placed.

The lower face of the fuselage is open, as indicated at 8, and the forward end is closed by the cap 9 having an opening 10 therein, forming a bearing for the forward end of the propeller shaft 11 which has secured thereon beyond the cap the propeller 12 which is of the usual two blade form, as clearly shown in Fig. 3 of the drawings. The rear end of the fuselage is provided with horizontal and vertical balancing planes 13 and 14 made of the usual shape and arranged as clearly shown and which needs no further description. The rear end of the fuselage adjacent the planes 13 and 14 is provided with the downwardly extending arms 15 and 16 forming bearings for the pintles 17 carried by the roller or wheel 18.

The propeller shaft extends approximately the entire length of the fuselage and the horizontal plane 14 has its inner end turned downwardly as indicated at 19 and forming a bearing for the propeller shaft 11. The shaft beyond the bearing has rigidly secured thereon a pulley 20 around which passes the drive belt 21 which also passes around the pulley 18. By this structure it will be seen that the roller 18 rests upon the ground or floor and is frictionally driven and whereby, through the medium of the belt 21, the propeller shaft 11 is driven.

The planes 22 and 23 are of metal and slightly convexed and held in their spaced relation by the rods 24 and 25 arranged at the proper intervals, as shown in Figs. 3 and 4. The forward edge of the lower plane is provided with an outwardly extending loop 26 made of wire, which extends around the propeller and protects the propeller when the toy runs against an obstruction.

The fuselage 1 is provided adjacent its

forward end with a solid lower end, as indicated at 27, and the solid end is provided with two openings or slots 28 arranged to correspond or register with openings or slots 29 in the lower plane 23.

The running gear consists of a longitudinal plate 30 having at its forward end upwardly and forwardly extending lugs 31 adapted to enter the slots 28 and 29 and 10 lock the planes, fuselage and the running gear together. The rear end of the plate 30 is provided with a slot 32 extending from the rear edge and adapted to register with a slot 33 extending from the rear edge of 15 the fuselage 27 and also with a slot 34 in the rear edge of the lower plane 23. Passing through the slots is a single bolt 35 which securely holds the running gear, the planes and the fuselage in the position fully shown 20 in Fig. 2 of the drawings.

The plate 30 is provided with a downwardly bent portion 36 resting upon a transverse plate 37 and held together by the pivot 38, whereby the wheels are pivotally supported, as will be hereinafter more fully described. The transverse plate 37 is provided with beveled faces 39 and 40 on each side of the pivot which will cause the plate 30 to tilt upon the turning of the same on 25 the pivot, and whereby the planes carried thereby are tilted. The plate 37 has its outer ends turned downwardly at 41 and 42 which have laterally turned lower ends riveted to the spring carrying case 43. The 30 case 43 is of the ordinary form now used on toys manufactured by us and in this form is provided with the horizontal shafts 44 and 45 driven by the spring and provided with the supporting wheels 46 and 47. The 35 lower end of the spring case is provided with the winding lugs 48 for winding the spring in the casing.

While there is shown in the drawings a toy of the above character running on the 45 ground or floor, it will be understood that a boat could take the place of the running gear and paddle wheels could be substituted for the wheels whereby a hydroplane would be formed to glide over the water.

Having thus described the invention, what 50 is claimed as new is:—

1. A toy of the character described, comprising a fuselage, planes and running gear made separate, and a common means for 55 securing the same together.

2. A toy of the character described, comprising a fuselage, planes and running gear made separate, interlocking means carried by the running gear for locking the forward 60 end of the same to the planes and locking the planes to the fuselage, and a bolt locking the rear end of the planes and the running gear to the fuselage.

3. A toy of the character described, com-

prising a fuselage, planes tiltably secured 65 thereto, a running gear carried by the fuselage for propelling the toy, and means causing said planes to tilt when said running gear is turned.

4. A toy of the character described, comprising a fuselage, planes secured thereto, and a running gear rotatable about a substantially vertical axis carried by the fuselage and having means for propelling the 70 toy.

5. A toy of the character described, comprising a fuselage, planes secured thereto, a propeller carried by the forward end of the fuselage, a friction wheel carried by the rear end of the fuselage having means for 80 rotating the propeller, and a running gear carried by the forward end of the fuselage and having means for propelling the toy.

6. A toy of the character described comprising a fuselage, planes secured thereto, a propeller carried by the fuselage, a friction wheel carried by the rear end of the fuselage and adapted to drive the propeller, and a running gear pivotally mounted and adapted to tilt the planes to one side upon the 85 turning thereof and having means for propelling the toy.

7. A toy of the character described, comprising a fuselage, propeller and planes, a running gear adapted to swing on a substantially vertical pivot for tilting the planes and having means for propelling the toy.

8. A toy of the character described, comprising a fuselage, propeller and planes, and a running gear secured to the fuselage, and 100 wheels mounted upon the substantially vertical pivot and adapted to tilt the planes, and means carried by the wheels for propelling the toy.

9. A toy of the character described, comprising a fuselage, a propeller carried by the forward end of the fuselage, a shaft carried by the propeller and extending to the rear end of the same, a pulley carried by the shaft, downwardly extending arms carried by the rear end of the fuselage, a friction drive wheel rotatably mounted in the lower end of the arms, a belt passing around the wheel and the pulley for rotating the propeller, and a running gear carried by 110 the forward end of the fuselage and having propelling means.

10. A toy of the character described, the combination with the planes and fuselage, of a plate having a downwardly inclined portion, and a running gear having propelling means, and a transverse plate arranged at the same angle as the first-mentioned plate and pivoted thereto and having beveled portions on each side of the pivot, 120 whereby the turning of the running gear tilts the planes.

11. A toy of the character described, com-

prising two planes spaced apart, a fuselage resting upon the lower planes, a propeller carried by the fuselage, and a running gear having propelling means and having up-

wardly and forwardly extending lugs passing through registering slots in the fuselage and plane, and a single bolt passing through

slots in the fuselage, plane and running gear.

In testimony whereof we affix our signatures.

EDWARD J. KINGSBURY.
HARRY T. KINGSBURY.
